UNITED STATES PATENT OFFICE

WILLIAM H. SOMMER, OF PEORIA, ILLINOIS

LUBRICATING DEVICE

Application filed October 13, 1930. Serial No. 488,361.

This invention has reference to a lubricating device and it has for its principal object to provide for the constant, efficient and economical lubrication of wires during the formation of wire strands and also the further lubrication of strands during the formation of a wire rope or cable.

The invention has for a further object, in the manufacture of wire strands and also in the manufacture of rope or cable from such strands, to lubricate the individual wires with a lubricant heated to a suitable temperature, whereby under cooling action of the wire the lubricant will tend to harden around each wire so that, during the action of pressing the wires together in the formation of the strands, the lubricant will fill all voids between such individual wires; furthermore, as the individual strands are closed into a rope or cable around a hemp or manila center, a heated lubricant is similarly applied so as to fill all voids between such individual strands.

While I have stated that the invention is applicable when forming the strands and also when forming a cable or rope from such strands, it is to be understood that, since each operation is a distinct operation, in itself, there is no necessary joinder of such uses, but that the application of the lubricant may be single or collective, as operations may require.

The invention comprehends the use of a feeder for the lubricant which is coupled to a preferably constant speed motor and pump, and with the discharge of the feeder located at a point to properly feed the lubricant between the interstices of the wires as they are woven or coiled into strands; the employment of heating means, as for instance steam piping arranged in a receptacle containing the lubricant, which said receptacle is adapted to catch drippings from the feeder to be again circulated therethrough; the use of a strainer through which the lubricant circulates to the pump and feeder and to a control for regulating the quantity and flow of the lubricant through the feeder; all of which said elements are assembled as a complete lubricating unit and readily attach-

able to a stranding machine or to a cable or rope machine.

The term "lubricant" as herein used has reference to any oil suitable for the purposes herein intended and in particular to "petrolatum".

That the invention may be more fully understood, reference is had to the accompanying drawings forming part of this description, illustrating a preferred embodiment of the invention, in which:—

Fig. 1 is a plan view illustrating a device embodying my invention, which is shown associated with a strand twister and closing die, and

Fig. 2 is an elevation in cross-section, as the same would appear if taken on the line 2—2 of Fig. 1.

Like characters of reference denote corresponding parts throughout the figures.

The drawings disclose a twisting element A of a stranding machine and a closing die B adjustably supported in relation to said twister. Fig. 2 shows the action of the closing die on the strand C as it is formed, by the twisting of the wires a fed through the twister and the preferred location of the discharge of the feeder to insure the lubricant reaching the individual wires a and the interstices of such wires. The number of wires shown threaded through the twister is illustrative only, as in practice there are, on the average, many more wires employed in the strand than is shown.

The lubricating unit comprises the constant speed motor 1; the pump 2 geared thereto; the strainer 3 through which the lubricant must pass to the pump; the feeder 4 leading from the pump to preferably a point immediately in front of the closing die to insure a proper oiling of the individual wires; a control valve 5 to regulate the quantity and flow of the lubricant through the feeder 4; a steam coil 6 connected with a suitable source of supply and which is placed along and over the bottom of a tank or receptacle 7 which holds the lubricant and in which the pump, strainer and control are located and from which the feeder leads to its point of discharge. The pan or recepta-

cle 7 is suitably supported on the frame of the stranding machine or an auxiliary support thereon and the said pan or receptacle is located and of such size that any excess 5 drippings or surplus lubricant which is not taken up by the wires will fall back into said pan or receptacle and be recirculated through the pump and feeder.

The feeder 4 is shown, by dotted lines, as 10 having a preferably slip-joint connection with the pump to permit its detachment from the pump which it is desirable to do at the close of the day and when the power to the motors is shut off.

15 The valve 5 may be opened and allow the oil pumped through the pump 2 to pass back into the pan or receptacle and also regulated and partially closed so as to regulate the quantity and flow of the oil through the feeder 4, and thus always insure feeding a maximum amount of oil that the wires and strand or cable will hold.

A feature of the herein described unit is, 20 that when the device is adjusted it will operate constantly and without stoppage or attention and until the attendant or operator wishes to stop it, and heating the lubricant by steam there is no fire hazard and by providing a comparatively large pan or receptacle 25 catches all drippings and surplus oil which is constantly recirculating. The only attention the device requires, is to supply new lubricant as the old is used up.

Stoppage of the stranding machine will 30 not affect the unit as it may continue in its operation, as it merely means a continuous circulation of the oil from the pan, through the pump and feeder and back again, and until the stranding machine is again started 35 up. Furthermore, no difficulties are encountered with proper and effective lubrication at the time of threading the stranding machine and attaching the strand to the take up, as the unit need not be stopped, but 40 continue its operation and thereby insure the entire strand, throughout, being properly lubricated.

I have made mention of the facts that the 45 device is applicable to cabling or rope machine, whereas the illustrations portray only its use in connection with a stranding machine, but since the cabling machine is merely the twisting of a series of strands C into a rope or cable, it will be obvious to those 55 skilled in the art that it will require nothing more than mere mechanical adaptation to apply the unit to such a cabling machine.

What I claim is:—

1. An oiling unit for lubricating the wires 60 of stranding and cabling machines, comprising a container for the lubricant, a heating coil on the bottom of the container, a pump within the container disposed above said coil, a strainer connected with the inlet end of 65 the pump, a feeder having a detachable con-

nection with the delivery end of the pump and having its discharge end above and pointing in the direction of the container, and a control valve for regulating the flow of lubricant through the feeder.

2. An oiling unit for lubricating the twisted wires of stranding and cabling machines, including a lubricant container, a heater within the container, a pump within the container, and a lubricant distributor connected to the delivery end of the pump whereby all of said elements are carried as a unit by the container, and means to mount the container beneath and in proximity to the points of closing of the wires and with the distributor disposed so that same will feed the lubricant to the wires at their points of closing.

3. An oiling unit for lubricating the twisted wires of stranding and cabling machines, including a lubricant container, a heater within the container, a pump within the container, and a lubricant distributor connected to the delivery end of the pump whereby all of said elements are carried as a unit by the container, and means to mount the container beneath and in proximity to the points of closing of the wires and with the distributor disposed so that same will feed the lubricant to the wires at their points of closing, said container being of a length so that a part thereof projects beyond the point of application of the lubricant and being located closely adjacent to such point so that any excess of distributed lubricant will gravitate directly into the container.
